UNITED STATES PATENT OFFICE.

HARRY BECKER, OF HULL, MASSACHUSETTS.

NON-REFILLABLE BOTTLE.

1,116,972.

Specification of Letters Patent. Patented Nov. 10, 1914.

Application filed March 20, 1914. Serial No. 826,105.

To all whom it may concern:

Be it known that I, HARRY BECKER, a citizen of the United States, residing at Hull, county of Plymouth, State of Massachusetts, have invented an Improvement in Non-Refillable Bottles, of which the following description, in connection with the accompanying drawing, is a specification, like characters on the drawing representing like parts.

10 This invention has reference to bottles of the type known as non-refillable bottles. Such bottles are so constructed that it is practically impossible or so difficult to refill them that re-filling would not be attempted commercially by retail dealers.

Certain types of liquid are sold by the manufacturer to retail dealers in large supply bottles and then re-sold in small quantities by the retailer to individual consumers.

20 It is an easy matter for dishonest retailers to re-fill bottles bearing the name and trademark of a well known manufacturer with cheap and inferior substitutes thereby cheating the customer and damaging the reputation of the manufacturer. For this reason there is a growing demand among manufacturers for non-refillable bottles, that is, bottles which the retailer cannot re-fill commercially.

30 The object of this invention is to provide an improved bottle of this type having a simple and cheaply constructed stopper which will automatically open when the bottle is inverted and automatically close and stay closed when the bottle is in any other position, thereby permitting the contents to be poured out but preventing the re-filling of the bottle by the retailer.

Another object is to provide an improved 40 bottle of this type having a movable valve and means to prevent the movement of the valve to open position when the bottle is in an upright or substantially upright position.

Another object is to provide means where- 45 by under certain conditions the valve will be locked in closed position.

The invention will be fully disclosed in the following specification and accompanying drawings and the novel features will be 50 particularly pointed out in the claims.

Referring to the drawings in which I have illustrated a preferred embodiment of my invention, Figure 1 is a sectional view of a bottle constructed in accordance with 55 the principles of my invention; Fig. 2 is a sectional view of the stopper showing the

parts in detail; Fig. 3 is a sectional view taken on the line 3—3, Fig. 1; and Fig. 4 is a sectional view taken on the line 4—4, Fig. 1.

60 Referring to the drawings in detail, the bottle which may be of any suitable or desired shape or size is indicated at 1 and has a long neck 2 preferably closed at its upper end by the usual cork crown seal or other removable closure, the former being illustrated at 3. In accordance with my invention a non-removable stopper in the form of a valve is positioned in the neck 2 preferably close to the body of the bottle. This stopper is 65 so designed that it automatically opens when the bottle is inverted, but closes and remains closed when the bottle is in any other position, and also closes automatically if it be attempted to force the liquid into the bottle 70

under pressure.

The stopper illustrated comprises a tubular member 4 having an upwardly presented valve seat 5 at its upper end and a downwardly presented conical cam surface 6 at 80 its lower end, with a closing member consisting of a valve stem 7, to the upper and lower ends of which respectively are secured a valve 8 and a weight 9 with a fulcrum member 10 slidably and rotatably 85 mounted therebetween. The weight 9 and the fulcrum member 10 are, in the preferred form, slidably mounted on the valve stem 7 and the stem 7 is provided with a head as indicated at 11 in Fig. 2. In the preferred 90 form also the valve stem 7 is tapered and the fulcrum member so fits upon this tapered spindle that if an attempt be made to fill the bottle by shaking it or by giving it sudden jars the fulcrum member will move up- 95

wardly and become wedged upon the valve stem in position close to the cam surface 6 and thereby prevent movement of the valve upward away from the valve seat 5 in response to such shaking. The stopper is 100 permanently fixed in position in the bottle and in the construction illustrated this is done by securing the tubular member in the neck of the bottle by sealing material 12. Cork or similar material of an expansive 105 nature is preferably employed for this purpose and the best results are secured by providing grooves or recesses 13 on the periphery of the tubular member 4 and so shaping the bottle as to provide an annular recess 14 110 on the interior thereof. Thus when the stopper and cork are forced into place the

cork expands into and interlocks with the grooves or recesses 13 and 14 and as access cannot be had, the cork forms the desired lock or seal. Preferably also the neck of 5 the bottle has a downward taper in the section occupied by the cork or sealing material by which it is further compressed and a tight fit under all conditions is insured.

The valve 8 is preferably of a generally 10 conical shape so that it may more readily be drawn to its seat when the bottle is returned to horizontal or upright position after pouring and it is preferably of spherical shape at that portion which engages 15 the seat to insure a perfect fit in all angular positions of the valve stem. The fulcrum member is positioned between the valve and weight to coöperate with the cam surface when the bottle is in a generally 20 horizontal position and slides thereon to draw the valve to the seat 5 and hold it there-against. It is of such a size that it cannot enter that part of the tubular member above the cam surface 6 and is of such a shape 25 that it will not interfere with the flow of liquid. This member is illustrated as having three radial fins 15 and centrally bored to receive the valve stem 7.

The tubular member 4 is provided with 30 two upwardly extending members 16 dia- metrically opposite each other to provide support for a pivoted locking member 17. These upwardly extending members are illustrated as forming support also for a 35 top plate or shield 18 which prevents access to the valve, the sealing material and the bottle interior.

The pivoted locking member 17 is of a 40 length to extend close to the valve 8 so that when the bottle is in upright position and the locking member hanging downward upward movement of the valve by any means is impossible. In its preferred form this locking member is sector-shaped so that even if 45 the bottle is tilted considerably to one side the locking member will still be in a position to prevent the unseating of the valve by engaging the center thereof and in the plane of its axis. The lower end of this member 50 is thickened as indicated at 19 to increase its weight and cause it to swing more freely. As a convenient method of connecting the locking member to the supports 16 I secure a pivot pin 20 in the supports and provide 55 collars 21 and 22 to retain the locking member in central position thereon and adapted to swing in the plane of the axis of the valve and valve stem.

The shape of the valve as previously de- 60 scribed is such that as it bears against the valve seat when the bottle is laid in a horizontal position, the valve tends to move to open position by sliding along the valve seat. In order to counteract this tendency the 65 weight is so proportioned and so spaced

from the bearing portion of the fulcrum member that it balances the weight of the valve 8 as the bottle is in horizontal position. By this expedient substantially the whole weight of the closing 70 member bears upon the cam surface, and hence slides down the cam surface to thereby draw the valve to its seat making it impossible to pour liquid into the bottle when in a horizontal position. Since the weight 75 9 is slidably mounted on the stem 7 the seating of the valve 8 is further insured. Any shaking or vibration given the bottle thus causes the valve and the weight to act successively forcing the valve to its seat to prevent any attempt surreptitiously to fill the bottle. 80

It will thus be seen that the device embodying this invention is of exceedingly simple construction. 85

The device in its preferred form comprises but few parts the tubular member presenting a valve seat and cam surface, the valve with its valve stem, the weight, the fulcrum member, the pivoted locking member and the shield which is rigidly secured to the tubular member. The parts are so shaped and constructed that there is practically no liability of their getting out of order or failing to properly operate. Ample space is al- 95 lowed for the liquid to be withdrawn from the bottle by pouring, and liquid of the greatest viscosity can readily be thus poured. The fulcrum member being freely revoluble and slidable on the valve stem acts automatically to clear the device of any sediment or slight obstruction which may get through with the liquid. When the parts are in place 100 it is practically impossible to reach, injure or mutilate them or to remove them from the 105 bottle. The parts are all concealed in the neck of the bottle so that the bottle presents the ordinary and usual appearance.

The several parts of the device may be made of any suitable material but obviously 110 of such a material that they will not impair or injure the contents of the bottle or be themselves subjected to corrosion, preferably therefore these parts will be made of material plated or covered with tin, porcelain or 115 the coating used on well known agate ware. The valve 8 proper may be made of other material, such as hard rubber if desired, or when practicable. It is only necessary that there should be a close fit between the valve 120 and its seat.

The fulcrum member and weight may be considered broadly as two weights. Both weights are loosely mounted upon the valve stem. Accordingly, certain advantages are 125 obtained, for example, when the bottle is given a vibrating movement, the weights operate against each other and thereby tend to prevent the unseating of the valve.

Having thus described my invention what 130

I claim as new and desire to secure by Letters Patent is;

1. The combination with a bottle, of a tubular member permanently secured in the neck of the bottle and having an upwardly presented valve seat and a downwardly presented cam surface, a closing member freely movable in said tubular member comprising a tapered valve stem, a valve secured thereto, a member slidably mounted on the valve stem and positioned to engage the tapered portion of the valve stem to be wedged thereupon and a shield positioned in the neck of the bottle to prevent access to the parts.
2. The combination with a bottle, of a tubular member permanently secured in the neck of the bottle and having an upwardly presented valve seat and a downwardly presented cam surface, and a closing member freely movable in said tubular member comprising a tapered valve stem, a valve and a weight connected thereto, a fulcrum member slidable on the valve stem between the valve and weight but so constructed that when in its uppermost position relative to said valve stem it will become fixed relative thereto and will engage the cam surface to prevent upward movement of said closing member.
3. In combination with a bottle, a tubular member of less diameter than the interior diameter of the bottle neck, means for sealing the same therein, said tubular member being constructed with a cylindrical upper portion and a constricted lower portion the upper surface of which is provided with a conoidal valve seat and the lower portion with a reversely arranged cam surface, a spherical valve adapted to engage said valve seat and having a rigid axial stem, a weight slidably mounted on said valve stem, a fulcrum member slidably mounted on said valve stem and adapted to engage said cam surface and a pivotally mounted locking member in said cylindrical chamber above said valve adapted to engage the same axially and to coöperate with said weight and fulcrum to seat said valve when the bottle is placed in any position other than a substantially upright or an inverted position.

In testimony whereof, I have signed my name to this specification, in the presence of two subscribing witnesses.

HARRY BECKER.
